UNITED STATES PATENT OFFICE.

JOHN STOW AND HARRY BARTON CROSS, OF BRADFORD, ENGLAND.

SLIDING DOOR FOR CASES, CUPBOARDS, AND THE LIKE.

1,303,984.

Specification of Letters Patent.

Patented May 20, 1919.

Application filed September 4, 1917. Serial No. 189,585.

To all whom it may concern:

Be it known that we, JOHN STOW and HARRY BARTON CROSS, subjects of the King of Great Britain and Ireland, residing at 5 Albert House, 38 Harrogate road, Eccles-hill, Bradford, in the county of York, England, and 16 Southey Place, Bradford, in the said county, England, respectively, have invented new and useful Improvements in 10 Sliding Doors for Cases, Cupboards, and the like, of which the following is a specification.

This invention relates to improvements in sliding doors for cases, cup-boards, shop-fitting entrances, and the like. Our object is 15 to arrange and construct sliding doors in such a manner that when they are closed they are rendered air tight, and further that when adjacent doors are closed they will be 20 in alinement.

Hitherto it has been found difficult, if not impossible, to make sliding doors air tight, and consequently dust-tight, when closed; although we are aware that attempts have 25 been made to overcome such difficulty by arranging doors to slide one in front of the other. Such doors however are not usually in alinement or in the same plane when closed. In some cases a brush device has 30 been attached to the rear face of the door to endeavor to overcome the dust nuisance.

According to our invention we arrange the doors in such wise that when closed they are air tight and dust-tight and are in alinement, and either of two adjacent doors may 35 be opened to move in front of the other, there being one track or groove which is common to both doors.

In describing our invention in detail reference is made to the accompanying sheet of 40 drawings, similar letters indicating similar parts in which:

Figure 1 represents a part elevation of doors fitted according to our improvement.

Fig. 2 represents a section showing one 45 door in the closed position with another in front thereof.

Fig. 3 represents a plan view of the upper track.

Fig. 4 is a plan view of the lower track and doors and

Figs. 5 and 6 represent details hereinafter referred to.

In carrying out our invention the sliding 50 doors D are constructed of any suitable ma-

terial such as wood, metal or a suitable frame and glass. The doors are by preference mounted in a framework D', each door having on its lower edge suitable runners such as R (Figs. 1 and 2) and such 60 runners are adapted to run on a suitable track P' (Figs. 2 and 4). In addition to the runners or wheels R ball bearings or the like, studs A A' are mounted on the door say one at or toward the bottom left hand 65 corner of the left hand door and another a little distance to the left of the right hand bottom corner. The arrangement of studs being reversed for the right hand door. In the example illustrated the studs are to the 70 rear of the doors. These studs carry what we term trackers T T' (Figs. 1, 2, and 4,) adapted to run horizontally in a groove, path or track P formed in or arranged in connection with the lower framework of the 75 opening which the door is to close. This path P is of such a nature as to guide say the right hand door in front of the left and vice versa, there being but one single track in front of and serving both doors. 80

In the top of each door there will also be mounted roller studs T^x to run in an upper track P^x, but the position of these studs may vary from that of the bottom ones. The paths P P^x are straight along the front of 85 the doors for the major portion, and sloping backward toward the doors to slightly behind same at the two ends as shown at P⁴ (Figs. 3 and 4).

To facilitate removal of a door for cleaning or repair purposes, the upper runners or rollers T^x will project upward in a line with the center of the door into the path P^x and apertures or recesses O (Fig. 2) at suitable places in the track may be provided into which the rollers T^x may take or enter when the door is lifted to clear the trackers T T' from their path. 90

Seeing that the trackers T T' are at the rear or inner sides of the doors when the 100 doors are closed the trackers T that is those nearest the handle edges of the doors will rest in recesses cut in the lower framework of the door openings, such recesses P² communicating with the path P. Similarly 105 recesses P³ will be cut back from the upper path P^x for the reception of those upper trackers or rollers T^x which are nearest the handle edges of the doors.

The center style D² between each pair of 110

doors may be of any desired width it not being necessary for the adjacent edges of a pair of doors to meet.

When the doors are closed, in the preferred form their inner faces toward their outer edges on 3 sides will be in contact with rubber, flexible, or other suitable beading B mounted in the framework of the door opening. On the fourth side the edge of the door will make contact with the beading B as will be seen from the drawings.

In the form shown the upper and lower beadings are made adjustable by being mounted in a beading carrier B' secured in place by screws B² or otherwise to allow for adjustment by altering the position of the screws and beading carrier (Fig. 2). This construction enables a recess to be formed under the beading carrier B' in which the trackers T are housed when the door is closed and so not affect the air tightness of the cupboard or case or like.

In some cases however a rubber or flexible beading may be replaced by a rounded solid beading to enter a rounded recess in the door frame or vice versa.

Any suitable handle such for example as H will be arranged in the doors in such wise that its bolt or nose H' will clip into or engage a nose or recess in the center stile D² and insure that the doors are drawn tight home against their beading when they are closed and latched. This handle being one that is lifted up to disengage and pressed down to engage. The arrangement of sliding doors and track hereinbefore described permits of the use of a projecting handle, projecting of course within limits of the space formed between a closed door and one open in front of it. This is a feature not common to doors made to slide one in front of the other hitherto known.

When the doors are closed their trackers will rest in their tracks or grooves or recesses P P^x P² and P³. To open a door its handle catch is released, the door pulled out until the trackers can come no farther out owing to the edge of the paths P P^x, the rear rollers or trackers acting as pivots. The door is then moved to the left or right as the case may be and is guided by the trackers in the paths P P^x the runners R before mentioned running on the solid track P' to the front of the path or groove P.

The top rollers or trackers will follow a similar path until when the door is completely open it will rest in front of the closed one, the position of each front tracker T being such that when the door is fully open the said tracker will not have passed into the curved or inclined portion P⁴ of the path P. Similarly with the bottom rollers.

In order that, when pulling the door for-

ward to open, there will be no undue jar or strain on the door, horizontal rollers C are formed by preference in connection with the tracker studs A to roll over the raised portion of the door opening framework until the runners R reach the track P', this device also serves to take away any cross strain from them. The rollers C are located at opposite sides of the intermediate branches P² of the longitudinal groove when the doors are closed, and the inner horizontal wheels or tractors have been moved into said branch grooves P² and they support the doors when the inner vertical wheels are over the branch grooves.

It is not however essential to place the trackers at the rear of the doors, they may be in front and under each end of the door. In this case the track or path P will be bifurcated at each end, there being the one straight track along the entire front of both doors with the inclined or curved portion P⁴ as above described and shown.

In Figs. 3 and 4 the doors are shown in their closed position by full lines, the left hand door is shown by dotted lines drawn out after the handle has been released from the stile and the door can now be moved along to the right. The dash and dot lines parallel with the closed door show the position of the right hand door when moved along the track in front of the left hand door.

We may vary the arrangement of the grooves slightly and may arrange the flexible beading to meet the face of the door in some directions, and the edge in others.

The doors will run easily, and when closed will be air-tight and adjacent pairs of doors will be in alinement. The form of handle and catch thereon to engage the door stile may vary, and there is no objection to a projecting handle within limits, so long as the locking action insures the door being drawn against its rubber or other flexible beading.

We prefer to use several balls or small wheels in the door base to act as bearings and such balls or wheels may be contained in separate casings—to insure that when crossing the runner groove when the runners are in front of the door there will be no liability of the door sinking or tending to sink.

What we claim as our invention is:

The combination of a track provided with a longitudinal groove having gently curved inwardly extending terminal portions and provided between its ends with short branch grooves extending inwardly at right angles to the longitudinal groove, a pair of sliding doors having vertical wheels to run on the track and horizontal wheels to operate in the said grooves, said horizontal wheels being received within the terminals of the

grooves and in the said branch grooves when
the doors are closed, and rollers carried by
the doors and located at opposite sides of
the branch grooves and supporting the doors
5 in their closed positions and when the same
are moved inwardly and outwardly.

In testimony whereof we have signed our

names to this specification in the presence of
two subscribing witnesses.

JOHN STOW.

HARRY BARTON CROSS.
